UNITED STATES PATENT OFFICE.

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,238,888.

Specification of Letters Patent.

Patented Sept. 4, 1917.

Application filed February 14, 1917. Serial No. 143,663.

To all whom it may concern:

Be it known that I, JOHN P. COLEMAN, a citizen of the United States, residing at Edgewood Borough, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus for the control of railway switches and the like.

I will describe one form of apparatus embodying my invention and will then point out the novel features thereof in claims.

In the accompanying drawings, Figure 1 is a view showing in section one form of valve and controlling apparatus therefor to which my invention may be applied. Fig. 2 is a view part of which is a fragmental section on the line II-II of Fig. 1 and the remainder of which is a diagrammatic representation of a railway switch and an operating motor therefor. Fig. 3 is a diagrammatic view showing one arrangement of controlling circuits for the apparatus shown in the preceding views, and embodying my invention.

Similar reference characters refer to similar parts in each of the several views.

Referring first to Fig. 2, the reference character A designates a railway switch. This switch is operated by a fluid pressure motor B, which motor is governed by an electromagnetically controlled valve apparatus C shown in Fig. 1 and in section in Fig. 2.

The motor B, as here shown, comprises a cylinder 1 and a piston 2 operable therein. The piston 2 is operatively connected with the rails of switch A through the medium of a suitable form of switch mechanism represented diagrammatically by the line 3.

The valve apparatus C, as shown in Figs. 1 and 2, comprises a valve body 5 provided with a valve chamber 8 in which is located a slide valve 9 which reciprocates in suitable guides on a valve seat 10, as shown in Fig. 2.

The valve seat 10 is provided with three ports 11, 12 and 13, of which port 12 communicates directly with atmosphere, and ports 11 and 13 communicate respectively with the left-hand and the right-hand ends

of cylinder 1. The slide valve 9 is of the usual D-valve type having a recess 18, so that when the valve is in one extreme position (as shown in Fig. 2) it connects the right-hand end of cylinder 1 with atmosphere and the left-hand end with valve chamber 8, whereas when the valve is in the other extreme position it connects the right-hand end of cylinder 1 with chamber 8 and the left-hand end with atmosphere.

The valve body 5 is provided with another chamber 21 to which fluid pressure, usually air, is constantly supplied from a suitable source through a pipe 25. Fluid pressure is at times supplied from chamber 21 to the valve chamber 8 through a valve 22 which is biased to the closed position by a spring 23 and by the action of the fluid pressure in chamber 21 on the back of the valve. This valve is provided with a stem 24 extending into chamber 8 and by means of which the valve may be opened at times, as will hereinafter be explained.

The valve body 5 is also provided with a cylinder 33 in which a piston 35 is adapted to reciprocate. Fluid pressure is supplied to the cylinder 33 from chamber 21 through ports 27 and 27^a, and the supply is controlled by a valve device 29 which in turn is governed by an electromagnet L, hereinafter termed the "lock magnet." Electromagnet L is provided with two windings l¹ and l², either of which when energized will actuate the armature of the magnet to operate the valve 29. The valve device 29 connects cylinder 33 with atmosphere through opening 31, or with chamber 21, according as the lock magnet L is deenergized or energized. Piston 35 is provided with a piston rod 35^a which passes through a cylindrical opening in the valve body and into the valve chamber 8, where it is operatively connected with a reciprocable plate 39 by means of a button 40 on the end of the piston rod 35^a and a jaw formed in the end of the plate. This plate 39 moves transversely to the direction of movement of the slide valve 9, and performs two functions, viz., to operate valve 22, and to mechanically lock the slide valve.

Considering the locking function first, the upper surface of the slide valve 9 is provided with three spaced transverse lugs 41, 42 and 43, thus providing slots into which

passes a tongue 16 formed on the under surface of plate 39. When the slide valve is in either extreme position the tongue 16 may pass into one or the other of the slots on the 5 valve and so lock the valve in the position which it occupies, as best shown in Fig. 2. When, however, the piston 35 is moved by the admission of fluid pressure to cylinder 33, it moves plate 39 so that the tongue 10 passes out of the slots in the slide valve whereupon the valve is free to be reversed. The other function of this plate 39, viz., the opening of valve 22 is accomplished merely by engagement of the end of the plate with 15 the stem 24 of valve 22.

When the lock magnet L is deenergized so that the outer end of cylinder 33 is connected with atmosphere through port 27^a and port 31, the action of the fluid pressure 20 in chamber 8 on piston rod 35^a moves piston 35 outwardly and the button 40 in turn moves plate 39 to the locking position, thus permitting valve 22 to seat, as shown in Fig. 1. The action of spring 23 and of the 25 fluid pressure in chamber 21 then holds valve 22 in the closed position, and after the pressure in chamber 8 has gradually escaped prevents the accidental unlocking of slide valve 9. The area of piston 35 is such, however, that when fluid pressure is admitted 30 to cylinder 33 by the energization of magnet L the pressure on this piston overbalances the combined forces acting on valve 22, so that plate 39 is then moved to the unlocking 35 position and valve 22 is opened, thus admitting fluid pressure to chamber 8. Plate 39 and valve 22 are, of course, immediately reversed upon the subsequent opening of cylinder 33 to atmosphere.

40 The slide valve is reciprocated by a fluid pressure motor device constructed as follows: In the valve body 5 are two axially aligned cylinders 44 and 45, in which are located pistons 46 and 46^a respectively. Integral with piston 46 is a rod 47, and with piston 46^a a similar rod 48, which rods pass through suitable stuffing boxes in the valve body and abut against the opposite ends of the slide valve 9. It will be clear, therefore, 45 that when the slide valve is unlocked, it may be reciprocated by alternately admitting fluid pressure to cylinders 44 and 45. The supply of fluid pressure for these cylinders is preferably taken from valve chamber 8. Cylinder 44 is connected with this chamber by ports 49 and 49^a, and the supply of fluid pressure to this cylinder is controlled by a 50 valve device 53 which in turn is governed by an electromagnet 51. Similarly, cylinder 45 is supplied by ports 50 and 50^a, and the supply is controlled by a valve device 54 governed by an electromagnet 52. The arrangement of each valve device 53 and 54, and its corresponding magnet is such that when the 55 magnet is deenergized the corresponding

cylinder is connected with atmosphere through a port 17 or 17^a, and that when the magnet is energized the corresponding cylinder is disconnected from atmosphere and is connected with the valve chamber 8. 70

Referring now to Fig. 3, I have here shown one arrangement of circuits and contacts for the control of the apparatus shown in the preceding views. The electromagnets 51, 52 and L are governed by a contact 57, 75 which is operated by a manually operable lever 56, which lever is one of a plurality of similar levers comprised in an "interlocking" machine. The windings of the lock magnet L are further controlled by a contact device M, comprising a movable contact 4 which is operatively connected with the switch operating mechanism 3 represented in Fig. 2, and which co-operates with fixed contact segments 4^a and 4^b. The operation 80 of the contact device M is such that when the motor B occupies one extreme position or the other contact 4 engages contact 4^a or 4^b. But when the motor occupies an intermediate position, contact 4 engages both the 85 contacts 4^a and 4^b.

It is understood that in practice suitable indication apparatus will be employed for controlling the movements of the lever contact 57 in accordance with movements of the 90 switch A, but in this view I have purposely omitted the indication apparatus and the circuits controlling such apparatus in order to simplify the drawing.

One terminal of magnet 51 is connected 100 with a "normal" wire N and one terminal of magnet 52 is connected with a "reverse" wire R. The remaining terminals of these magnets are connected with a common wire O by wires 14 and 7 respectively. One terminal of a battery 6 is connected with the common wire O and the other terminal is connected with contact 57, which contact in turn engages with contact 57^a or 57^b, which two latter contacts are connected respectively 105 with the "normal" and "reverse" wires N and R. It will be seen from the circuits thus far described that magnet 51 or magnet 52 will be energized according as contact 57 110 engages with fixed contact 57^a or 57^b. 115

As hereinbefore explained, the magnet L comprises two windings L' and L'', one terminal of winding L' is connected with the "normal" wire N, and one terminal of L'' is connected with the "reverse" wire R. The remaining terminals of these windings are connected respectively with fixed contacts 4^b and 4^a. This arrangement of control of the lock magnet L is such that when the switch A and the controlling lever 56 coincide in 120 position, both windings of magnet L are deenergized; whereas, when the controlling lever is swung to reverse the position of the switch, one winding or the other of magnet L becomes energized and continues to be en- 125 130

ergized until the switch has completed its movement in response to such movement of the lever 56.

The operation of the apparatus is as follows:

The switch A, as shown in Fig. 2, occupies what I will term the "normal" position, and all parts of the apparatus connected thereto occupy corresponding positions. When it is 10 desired to reverse the position of switch A, the manual lever 56 (Fig. 3) is swung upwardly through a portion of its stroke until it is stopped by the indication apparatus in such position that the movable contact 57 is in engagement with fixed contact 57^b. Winding 7^a of lock magnet L is now energized and the energization of this magnet causes the admission of fluid pressure from chamber 21 to cylinder 33 thereby causing 15 operation of the piston 35 to unlock the slide valve 9 and open valve 22, thus admitting fluid pressure to the valve chamber 8. Magnet 51 is now deenergized so that valve 53 reverses to connect cylinder 44 with atmosphere. Magnet 52 is energized so that valve 54 is reversed to admit fluid pressure from the chamber 8 to cylinder 45 whereby the slide valve 9 is shifted to the left, as viewed 20 in Fig. 1. This causes the admission of fluid pressure to the right-hand end of cylinder 7, as viewed in Fig. 2, so that switch A is then moved to the reverse position through the medium of the switch operating mechanism 3. When the movement of the switch is completed and the switch has been properly 25 locked, contact 4 engages with contact 4^b and becomes disengaged from contact 4^a, so that winding 7^a becomes deenergized. Lock magnet L is now totally deenergized so that 30 valve 29 reverses and disconnects cylinder 33 from the source of fluid pressure and opens this cylinder to atmosphere, whereupon piston 35 reverses to close valve 22 and lock the slide valve 9 in its extreme left-hand 35 position, as viewed in Fig. 1.

The operation of the apparatus for movement of the switch A from its "reverse" to its "normal" position is similar to the operation just explained, winding 7^a of lock magnet L being energized during such operation.

One feature of the apparatus hereinbefore described, is that while the switch and its controlling lever coincide in position, the lock magnet L is deenergized so that it is 40 impossible to cause movement of switch A by manipulation of valves 53 and 54 or by improper energization of magnets 51 and 52. If, however, an unauthorized attempt is made to shift the switch away from the position corresponding to the position of its controlling lever by means other than such lever, magnet L will at once become energized and will admit fluid pressure to chamber 8 and so to the operating motor B, thus causing this 45 motor to oppose such attempt.

Although I have herein shown and described only one form of railway traffic controlling apparatus embodying my invention, it is understood that various changes and modifications may be made therein within 70 the scope of the appended claims without departing from the spirit and scope of my invention.

Having thus described my invention, what I claim is:

1. In combination, a railway traffic controlling device, a fluid pressure motor for moving said device, two valves controlling said motor to cause reverse movements thereof, two electromagnets one for each 80 valve, a lever, contacts and connections controlled thereby for energizing one electromagnet or the other, and means controlled jointly by said contacts and connections and by said motor for interrupting the supply 85 of fluid pressure to the motor when the motor and the lever coincide in position.

2. In combination, a railway traffic controlling device, a fluid pressure motor for moving said device, two valves controlling 90 said motor to cause reverse movements thereof, two electromagnets one for each valve, a lever, contacts and connections controlled thereby for energizing one electromagnet or the other, and means controlled 95 jointly by said contacts and connections and by said motor for interrupting the supply of fluid pressure to the motor upon completion of a movement of the motor in response to a movement of the lever.

3. In combination, a railway traffic controlling device, a fluid pressure motor for moving said device, two valves controlling said motor to cause reverse movements thereof, two electromagnets one for each 100 valve, a lever, contacts and connections controlled thereby for energizing one electromagnet or the other, and means controlled jointly by said contacts and connections and by said motor for preventing inadvertent 105 movement of the motor by unwarranted manipulation of said valves when the lever and the motor coincide in position.

4. In combination, a railway traffic controlling device, a fluid pressure motor for moving said device, two valves controlling said motor to cause reverse movements thereof, two electromagnets one for each valve, a lock magnet for also controlling said motor, a lever, contacts and connections controlled 115 by said lever and by said motor for energizing said lock magnet when the lever and the motor do not coincide in position, said lever controlled contacts also serving to energize one of said valve controlling electromagnets 120 or the other.

5. In combination, a railway traffic controlling device, a fluid pressure motor for moving said device, two valves controlling said motor to cause reverse movements there- 130

of, two electromagnets one for each valve, a lever, contacts and connections controlled thereby for energizing one electromagnet or the other, and a lock magnet controlled jointly by said contacts and connections and by said motor for preventing movement of said motor when the motor and the lever coincide in position.

6. In combination, a railway traffic controlling device, a fluid pressure motor for moving said device, two valves controlling said motor to cause reverse movements thereof, two electromagnets one for each valve, a lever, contacts and connections controlled thereby for energizing one electromagnet or the other, a lock magnet having two windings, and means controlled by said contacts and connections and by said motor for energizing one of said windings or the other 20 when the motor occupies either extreme position and the lever is in non-coinciding position, and for deenergizing both of said windings when the lever and the motor coincide in extreme positions.

25. 7. In combination, a railway traffic controlling device, a fluid pressure motor for causing reverse movements of said device, a normal and a reverse valve for controlling said motor, a normal and a reverse electromagnet for controlling said two valves respectively, a normal and a reverse wire, and a common wire, one terminal of each electromagnet being constantly connected with

said common wire, and the remaining terminals of said normal and reverse magnets 35 being connected with said normal and reverse wires respectively, a source of current one terminal of which is constantly connected with said common wires, a lever, contacts controlled by said lever for connecting 40 the normal or reverse wire with the remaining terminal of said source, a lock magnet comprising two windings, one terminal of one winding being connected with the normal wire and one terminal of the other winding being connected with the reverse wire, and contacts controlled by the motor for connecting the remaining terminal of one of said windings on the other with the common wire according as the motor is in one 45 extreme position or the other, and for connecting both of said last-mentioned terminals with the common wire when the motor occupies an intermediate position, the winding which is thus connected with the common wire when the motor is in an extreme position being the one which is not connected with the source of current through the normal or reverse wire when the lever occupies the corresponding extreme position. 50

55. In testimony whereof I affix my signature in presence of two witnesses.

JOHN P. COLEMAN.
